COMBINED HEATER AND MASSAGER

Clifford E. Grube, Chicago, Ill., assignor to Associated Mills, Inc., a corporation of Illinois

Filed Dec. 21, 1964, Ser. No. 83,108

Term of patent 14 years

(Cl. D83—1)

I claim:

The ornamental design for a combined heater and massager, substantially as shown.
